UNITED STATES PATENT OFFICE.

WILLIAM N. BEST, OF NEW YORK, N. Y.

MELTING-FURNACE.

1,137,378.

Specification of Letters Patent. Patented Apr. 27, 1915.

Application filed May 31, 1913. Serial No. 770,947.

To all whom it may concern:

Be it known that I, WILLIAM NEWTON BEST, a citizen of the United States, and resident of New York city, in the borough 5 of Brooklyn, county of Kings, and State of New York, have invented certain new and useful Improvements in Melting-Furnaces, of which the following is a specification.

This invention relates to certain improvements in melting furnaces, and more particularly to a type of furnace adapted for use in melting metals or alloys in portable crucibles. It is well-known that checker work or regenerators can not be used efficiently in furnaces of this type when melting brass, as such checker work or regenerators soon become obstructed by deposits from the gases or fumes resulting from the heating of the alloy to a high temperature. In 10 my improved construction I so arrange the combustion chamber, the melting chamber and the flues to the stack that I utilize a considerable portion of the waste heat and preheat the incoming air before delivering 15 the latter to the combustion chamber. In the preferred construction, I provide two combustion chambers at opposite ends of the body of the furnace and connect the stack to the furnace by separate flues leading 20 to the two combustion chambers. Each flue adjacent the stack is provided with suitable controlling means whereby communication 25 with the stack is shut off and communication established either directly with the atmosphere or with the source of gas supporting combustion. Normally the body of 30 the furnace is heated from only one of said combustion chambers, the air or other gas supporting the combustion entering through 35 one of said flues and the gases of combustion and the fumes or gases from the metal alloy or other material being heated passing out through the other flue to the stack. The 40 flues are so constructed as to absorb and retain heat and a large portion of the waste 45 heat of said gases and fumes will be absorbed and retained by the walls of the second-mentioned flue. The operation may be reversed for successive charges of material 50 to be heated or at as frequent intervals as desired depending for instance, on the time required to heat or cool the walls of the flues. After each reversal in the operation 55 the air will enter the combustion chamber through the flue which has just previously been heated by the outgoing gases

of combustion and the flue through which the air has previously entered will be heated preparatory for the next operation.

The main principle of operation of my 60 improved furnace is preferably as above outlined, but the structural details may be varied in various ways without departing from the spirit of my invention. Furthermore, certain structural features hereinafter 65 pointed out are in themselves important and may be used in furnaces of other types or operating on other principles.

Reference is to be had to the accompanying drawings in which I have illustrated 70 one form which my invention may assume, but I desire the drawings to be considered in an illustrative rather than in a limiting sense. In these drawings, in which similar reference characters indicate corresponding 75 parts throughout the several views, Figure 1 shows a top plan view of a furnace embodying my invention; Fig. 2 is a partial plan view and partial section on the line 2—2 of Fig. 3; Fig. 3 is a vertical longitudinal section on the line 3—3 of Fig. 2; Fig. 4 is a vertical transverse section on the line 80 4—4 of Fig. 1; Fig. 5 is a vertical section on the line 5—5 of Fig. 1 and showing the connections between the flues and the stack; 85 and Fig. 6 is a view similar to a portion of Fig. 5, but showing a slightly modified construction.

In the specific form shown in the drawings, I provide a heating chamber sub-divided 90 into two compartments 10 and 10^a, by a partition 11, having an aperture 12 therethrough. The two compartments of the heating chamber at their outer ends communicate with combustion chambers 13, 13^a, 95 within which the heat is generated and from which it is delivered to the heating chamber. The combustion chambers taper inwardly from comparatively small outer apertures, 14 and 14^a. The side walls of each combustion chamber extend at an angle to each other, from the side walls of the heating chamber to the corresponding outer opening and the top and bottom walls of each combustion chamber spread apart as they extend 100 inwardly, so as to substantially merge with the top and bottom of the heating chamber. Thus each combustion chamber is substantially 105 an extension of the heating chamber and substantially triangular in both horizontal and vertical section as is indicated in Figs. 2 and 3. Opposite the outer ends of

the combustion chambers are burner chambers 15, 15^a within which are located burners 16, 16^a of a type adapted to deliver a fan-shaped body of oil or other fluid fuel into the combustion chamber the fan-shaped spray or body of fuel extending across substantially the entire width of the combustion chamber and thus filling the latter transversely and along substantially its entire 5 length. The burner which I preferably employ is of the general character indicated in my prior Patent No. 752,195 granted February 16th, 1904, or that shown in the patent to W. N. Best, Jr., No. 963,985, granted July 10 15 12th, 1910. The entrance openings 14, 14^a to the combustion chambers are of such shape and size and the burners are so placed that very little combustion supporting air enters the openings. The burner may use 20 either compressed air or steam for forming the liquid spray and delivering it to the combustion chamber in case a liquid fuel is employed.

In the bottom wall or floor of the combustion chambers adjacent their outer ends are ports 17, 17^a communicating with flues 18, 18^a leading to the stack 19. These flues serve to alternately deliver combustion supporting medium to the combustion chamber and to 25 conduct from the heating chamber the gases of combustion and fumes from the material being heated, as will be more particularly hereinafter pointed out. Adjacent the combustion chamber inlet ports 14, 14^a are two 30 dampers 20, 20^a which may be of a very simple character and may be merely in the form of slides which may move across and close the port. In the flues 18, 18^a adjacent to the stack are two dampers 21, 21^a which may be 35 operated to control the communication between the flues and the stack. Adjacent these two dampers 21, 21^a and on the side thereof away from the stack are air inlet 40 ports controlled by dampers or valves 22, 22^a. These controlling means 21, 21^a, 22 and 45 22^a, may be of any suitable character and may be operated in any suitable manner, but preferably they are so constructed that when one of the dampers 21, 21^a is open the corresponding damper 22 or 22^a will be closed and vice versa. The flues 18, 18^a are of any suitable length dependent upon the relative location of the stack and upon the degree of 50 preheating which it is desired to impart to the incoming combustion supporting medium. The walls of the flues are preferably formed of fire brick or of other suitable material which will not be injured by the heated gases or by rapid changes in temperature, 55 and are preferably of such a character that they will absorb and retain a large amount of heat from the hot gases so as to later impart it to the incoming air.

In the operation of the furnace so far as 60 above described crucibles 23 are placed in

the heating chambers, said crucibles being charged with the material to be heated either before or after being placed in position. One of the burners for instance the burner 16, is started in operation, the corresponding 70 damper 20 having previously been opened and the opposite damper 20^a closed. The dampers 21^a and 22 will be open and the dampers 21 and 22^a will be closed. In other words, these parts will be in the reverse position from that shown in Fig. 5. The necessary air to support combustion will enter the port uncovered by the damper 22, and will flow through the flue 18 and port 17 to the combustion chamber 13. The hot gases and 75 the fumes from the material being heated will pass out through the port 17^a and through the flue 18^a to the stack. This operation is continued either until the material in the crucibles has been melted or, for any 80 shorter or longer length of time desired. The operation is then reversed by shutting off the burner 16 and starting the burner 16^a and opening the dampers 20^a, 21 and 22^a and closing the dampers 20, 21^a and 22. The 85 air will now enter through the flue 18^a and will be preheated by the heated walls of the flue, while the hot gases escape through the flue 18 and will heat the walls of the latter 90 preparatory to the next reversal of operation. 95

I have shown the dampers 21 and 21^a in the form of vertically movable slides and the dampers 22 and 22^a as pivotally mounted valve plates. As shown the dampers 22, 100 22^a have lever extensions 24, 24^a and the dampers 21, 21^a have outwardly extending lugs 25, 25^a which may engage with these lever extensions to tilt and open the pivoted dampers when the sliding ones are lowered 105 into position. Gravity is relied upon to close the pivoted dampers when the sliding ones are raised. As far as the operation above described is concerned the construction of these dampers might be very radically altered as it is only essential that the flues have suitable means whereby communication with the stack may be controlled, and air admitted adjacent to the controlling means. It is noted that the dampers 22, 22^a 110 open to a predetermined and definite degree when the dampers 21, 21^a are raised. The admission of air is preferably controlled in accordance with atmospheric conditions by means of auxiliary, readily controllable 115 dampers. In Fig. 6 I accomplish this by a supplemental air inlet port 26 adjacent to the port controlled by the damper 22^a and having a sliding damper 27 for controlling said port 26. When it is desired to secure 120 a strong draft through the stack these adjustable dampers 27 may be closed as for instance upon a humid or particularly warm day. It is evident that the dampers may be 125 controlled in any manner desired to secure 130

the results sought or may be entirely omitted.

The dampers 21, 21^a are shown with rings or loops 28, 28^a at their upper ends and suitable levers, cords or other operating mechanism may extend from these dampers to the opposite side of the furnace or to any other suitable position from which it is desired to operate them. I have not illustrated such operating means as it is evident that any suitable arrangement of levers or cords and pulleys might be employed for the purpose.

I have shown each heating chamber as containing a single row of three crucibles, but it is of course evident that the size of the heating chamber may be varied with the work to be accomplished, and any desired particular size and arrangement of crucibles may be employed. These crucibles are illustrated as being supported on blocks 29 of refractory material, the blocks being so positioned as to insure a predetermined arrangement and spacing of the crucibles.

The entire top of the heating chamber is preferably made up of separate removable sections 30 which may be lifted off by any suitable hoisting mechanism, for instance block and tackle, piston and air cylinder or a suitable arrangement of levers. These may of course be designed in accordance with the desire of the operator or adapted to the particular position or location of the furnace. Each top section 30 is preferably provided with a central aperture 31 located above the corresponding crucible and through which the latter may be charged or inspected. Any suitable closure 32 may be employed for this aperture. Preferably the inner walls of these closures as well as the walls of the heating chamber are lined or covered with refractory material.

Another important feature of my construction involves the special provision shown for receiving any material which may be spilled from the crucibles or which may drop into the heating chamber beside the crucibles or to receive the material escaping from a crucible upon the cracking, breaking or overturning of the latter. The bottom wall of the heating chamber is preferably inclined laterally and adjacent to the heating chamber is a secondary chamber or catch

basin chamber 33. Within this chamber may be placed crucibles 34 and a series of outlet ports 35 lead from the bottom of the lower side of the heating chamber to the secondary chamber, so as to deliver into the crucibles 34. The secondary chamber may have removable covers 36 and preferably flues 37 lead from the secondary chambers 36 directly to the stack, so that the fumes and heated gases from the secondary chambers may pass directly to the stack. This is particularly important where lead or other readily volatile metal is being melted. The removable covers to the heating chamber and the secondary chambers as well as the large size of the flues 18, 18^a permit the ready cleaning of said chambers and flues to remove accumulation of deposits. If the burners be properly regulated and the proper amount of air be delivered to the combustion chambers such deposits should contain little or no soot.

Having thus described my invention, what I claim as new and desire to secure by Letters-Patent is:

1. In combination, a heating chamber, a stack, two separate flues serving to connect said chamber with said stack, means for delivering fluid fuel to each end of said chamber, each of said flues having an air inlet port, means intermediate said stack and the port for closing communication through the flue to the stack, a drainage chamber from said heating chamber and a flue from said drainage chamber to said stack.

2. A furnace including a heating chamber, a combustion chamber at one end thereof and having a fluid fuel inlet port, and an air inlet port, a stack, a flue connecting the opposite end of said heating chamber with said stack, a drainage chamber connected with said heating chamber, and a separate flue connecting said drainage chamber and said stack.

Signed at New York in the county of New York and State of New York, this 26th day of May, A. D. 1913.

WILLIAM N. BEST.
